BOX STACKER

Ambrose Neja, Anaheim, Calif.

Application February 15, 1943, Serial No. 475,913

7 Claims. (Cl. 214—6)

This invention relates to a box stacking apparatus.

The general object of the invention is to provide an improved box handling apparatus whereby boxes may be stacked and the stack may be moved to a desired location.

This invention is an improvement on the construction shown in my copending applications Serial No. 390,737, filed April 28, 1941, and Serial No. 435,013, filed March 17, 1942, now Patents 2,313,478 and 2,329,413, granted March 9, 1943, and September 14, 1943, respectively, and the novelty in the present application resides primarily in the relation between the discharge conveyor and the elevator and in the means for operating the discharge conveyor and the elevator so that the boxes are stacked and a stack removed in an improved manner.

A more specific object of the invention is to provide an improved apparatus for stacking boxes one upon the other.

Another object of the invention is to provide a novel means for operating the elevator of a box stacking apparatus.

A further object of the invention is to provide a novel discharge conveyor and novel means for operating the discharge conveyor of a box stacking apparatus.

Other objects and advantages of the invention will be apparent from the following description taken in connection with the accompanying drawings, wherein

Fig. 1 is a plan view of my improved stacking and conveying mechanism;

Fig. 2 is a rear elevation;

Fig. 3 is a view similar to Fig. 2 with parts in section and with parts in different position;

Fig. 3A is a sectional detail taken on line 3A—3A, Fig. 3;

Fig. 4 is a view similar to Fig. 3 with other parts in section and with parts in different positions from that shown in Figs. 2 and 3;

Fig. 5 is a side elevation partly in section;

Fig. 6 is a wiring diagram for controlling the motor operation of the box stacking mechanism;

Fig. 7 is a wiring diagram for controlling the motor operation for the box conveying mechanism;

Fig. 8 is a sectional detail with parts broken away showing one of the extensible swing arms.

Fig. 9 is a plan view of the elevator platform;

Fig. 10 is a sectional elevation view of the elevator platform taken on line 10—10, Fig. 9;

Fig. 11 is a detail taken on line 11—11, Fig. 3;

Fig. 12 is a perspective schematic view of the discharge conveyor raising control mechanism;

Fig. 13 is an enlarged sectional view taken on line 13—13, Fig. 11, with parts in elevation;

Fig. 14 is a sectional view taken on line 14—14, Fig. 11;

Fig. 15 is a view similar to Fig. 14 with the parts in another position, and

Fig. 16 is a sectional view of one of the eccentrics shown in Figs. 11 and 12.

Referring to the drawings by reference characters, I have shown my invention as embodied in a box handling apparatus which is indicated generally at 10. As shown the apparatus includes a feed conveyor 11, a stacking mechanism 12, and a discharge conveyor 13. As shown the feed conveyor 11 includes frame members 14 shown as made of angle iron with a cross piece 15 connecting members 14.

The frame members 14 each include an inwardly extending leg 14' secured thereto by welding. Secured to the frame members 14 at the end thereof remote from the stacking mechanism 12 I show bearing blocks 16 which support a shaft 17 having a pair of sprockets 17' secured thereto and arranged between the frame members 14. As shown the shaft 17 extends on one side beyond the adjacent frame member 14 and has a sprocket 18 secured thereto. The sprocket 18 by means of a continuous chain 19 drives a sprocket 20 on a shaft 21 which is supported by blocks 22 which in turn are supported at the outmost ends of the frame members 14. The shaft 21 drives a belt conveyor 23 which may be extended to any desired location and is adapted to transport boxes to the feed conveyor.

The frame members 14 at the end thereof adjacent to the stacking mechanism 12 support a shaft 24 journaled in bearing blocks 25 secured to the frame members 14. The shaft 24 has a pair of sprockets 26 secured thereto and arranged between the frame members 14. Sprockets 26 and the sprockets 17' support a pair of substantially parallel continuous chains 27.

The shaft 24 extends beyond one of the frame members 14 and has a sprocket 28 thereon which supports one end of a continuous chain 29 which is driven by a sprocket 30 from a motor 31. Thus it is seen that the motor 31 by means of the chain 29 drives the shaft 24 which drives the chains 27 which by means of the chain 19 drives the belt conveyor 23.

The frame members 14 intermediate the lengths thereof pivotally support a shaft 32 which supports a transverse bar 33 to which one end of

channel guides 34 are secured. The forward ends of the channel guides 34 are downwardly inclined as at 35 and a cross piece 36 is secured to the guides adjacent to the inclined portions 35. A lever 37 is provided with a bearing block 37' (see Fig. 4) which is pivotally supported on the shaft 24 between the sprockets 26. The rear end of the lever 37 includes an upwardly extending rod 38 adapted to engage the cross piece 36. Pivotally mounted on the shaft 32 I provide a downwardly inclined, forwardly extending rocker arm 39 which has a switch 40 mechanism mounted thereon. The switch 40 has an operating arm 41 and a roller 42 thereon, the roller 42 being positioned between the channel guides 34. The switch 40 controls the motor 31.

Secured to the transverse bar 33 I provide a forwardly extending plate 43 disposed between the channel guides 34. A splinter shield 44 is disposed between and connected to the channel guides 34. Between the plate 43 and the shield 44 and pivotally connected to the rocker arm 39 I provide at 44' an upwardly, then forwardly and then downwardly extending switch arm 45 which is adapted when rocked to engage the switch roller 42. Thus it will be seen that the forward ends of the chains 27 may be raised and lowered by rocking the lever 37 and the construction is such that when in the raised position the chains 27 are slightly above the inwardly extending leg 14' of the frame members 14 and when in the lowered position the chains 27 are slightly below the inwardly extending leg 14'. It will also be seen that the switch 40 may be raised and lowered by rocking the rocker arm 39 and the construction is such that when the chains 27 are in the raised position and the switch 40 is in the raised position (see Fig. 4) a box conveyed by the chains will engage and depress the switch arm 45 to thus actuate the switch 40 and shut off the motor 31 and stop the operation of the entire feed conveyor.

When the switch 40 is in raised position and the chains 27 are in the lowered position (see Fig. 3), a box being conveyed by the chains will engage and depress the switch arm 45 and thus actuate the switch 40 to shut off the motor 30 and thus stop the operation of the entire feed conveyor. Thus boxes are prevented from bunching up adjacent the stacking mechanism. When the switch 40 is in lowered position and the chains 27 are in raised position a box being conveyed by the chains will not depress the switch arm 45 far enough to actuate the switch 40.

A stop member 46 at the forward ends of inwardly extending legs 14' is positioned so as to engage the forward end of a conveyed box when the chains 27 are in lowered position, but when the chains 27 are in raised position the boxes will be raised by the splinter shield 44 and will pass over stop member 46.

As shown the stacking mechanism 12 includes a plurality of upright frame members 60, 60a, 60b and 60c. The frame members 14 are secured to the members 60 and 60a at the upper ends thereof, the upright members 60b and 60c are joined by a longitudinal cross member 61 while the members 60 and 60a are joined by transverse member 62 and members 60b and 60c are joined by a transverse member 62'.

A shaft 63 is supported on the upright members 60 and 60a, being journaled in bearing blocks 64. A shaft 65 is journaled in bearing block 66 on the upright members 60b and 60c. 75

The shaft 63 has a cylinder 67 secured thereto. The cylinder 67 has a sprocket 68 at one end thereof which is driven by a chain 69. The chain 69 is supported and driven by a sprocket 70 secured to the shaft 24.

On each of the shafts 63 and 65 I pivot a pair of spaced box engaging arms 71. The arms 71 extend upwardly and at the upper ends thereof are bent inwardly and joined by cross channels 72. Adjacent the upper bent portions each arm has an elongated rod 73 thereon. The rods 73 extend outwardly and through apertures in brackets 74 on the upright members 60, 60a, 60b and 60c. A nut 75 threadedly engages each rod 73 and the outer face of the brackets 74 to limit the movement of the arms 71. A compression spring 76 disposed about each of the rods 73 between the arms 71 and the brackets 74 normally urges the arms inwardly.

20 The lower portions of the arms 71 are supported on the shaft 65 by bearing portions 77 (see Fig. 5), the arms being secured to the bearing portions by bolts 79. The lower portions of the arms 71 (see Fig. 8) on the shaft 63 each include a bearing portion 80 having an upwardly extending bar portion 81 thereon to which the lower portion of the associated arm 71 is secured by bolts 82.

30 The bar portions 81 have slots 83 therein through which the bolts 82 extend to thus permit relative vertical movement of the upper portions of the arm 71 and the bar portions 81. The bearing portion 80 has an outwardly extending boss 84 thereon having an aperture 85 therein which one end of a tension spring 86 is secured. The other end of the spring 86 is secured to an outwardly extending boss 87 secured to the upper portion of the arm 71.

35 Adjacent the feed conveyor, a transverse angle member 95 extends between and is secured to the uprights 60 and 60a. The member 95 has a loop member 96 (Fig. 3A), secured thereto and depending therefrom. The loop member 96 supports the rocker arm 39 and permits limited vertical movement thereof.

40 At the bottom of the frame, a transverse angle member 97 is secured to the lower ends of the uprights 60 and 60a and a transverse angle member 98 is secured to the lower ends of the uprights 60b and 60c. As shown, members 97 and 98 extend beyond the uprights 60 and 60c and at its outer end, member 98 is secured to a vertical angle member 99. Opposite the transverse member 95 is a transverse member 100 secured to the uprights 60b and 60c and at one end thereof extends beyond the upright 60c and is secured at its outer end to the upper end of the vertical member 99.

45 Secured to the transverse members 95 and 100 I provide a pair of longitudinal angle members 101, each of which has one end of a transverse channel member 102 secured thereto. A pair of longitudinal angle members 103 are secured to the uprights 60 and 60c, and 60a and 60b, and each has one end of a transverse channel member 104 secured thereto. To the channels 102 and 104 I secure opposite ends of a cylindrical sleeve 105 through which an elongated tube 106 slides. A rectangular head member 107 on top of the tube 106 supports an elevator platform 110 which includes a plate member 111 secured to the head member 107 and having an angle bar 112 secured at one end thereof and a vertical plate 113 secured at the other end thereof.

50 A plurality of shafts 113' are mounted on the

vertical leg of the angle bar 112 and the vertical plate 113 and extending therebetween support rollers 114 the tops of which project slightly above the vertical leg of the angle bar 112 and the plate 113. One of the intermediate shafts 113' supports end flanges 115 on an apron 116.

Adjacent the roller 114 upon which the arms 115 are attached, plate 116 thereof has a downwardly extending portion 117. On the lower side of plate 116 and in the approximate middle thereof, I provide a rod 118, secured thereto by a welding, and extending downwardly to slidably engage a stop member 119 which is attached to the upper face of plate 111. A nut 118" threadably engages the lower end of rod 118. A spring 116' surrounds the rod 118 and is adapted to engage the lower face of plate 116.

A channel 120 extends between the extended portions of angles 97 and 98 (see Figs. 1 and 5) and a channel 121 extends between the angles 97 and 98 adjacent the uprights 60 and 60c. An angle member 122 extends between the members 87 and 98 adjacent the uprights 60a and 60b. An electric motor 123 is mounted on the channel members 120 and 121. An electric motor 123 is mounted on the channel members 120 and 121. The motor 123 by means of a reduction gear 124 drives a shaft 125 on which a gear 126 is mounted. The gear 126 is adapted to drive a large gear wheel 127 mounted on a shaft 128 which is journaled in a bearing bracket 129 on the vertical angle member 99 and in a bearing bracket 129' on a vertical angle member 131 extending between the members 98 and 100 and disposed between the uprights 60b and 60c. In Figs. 2, 3 and 4 the gear 126 drives the gear wheel 127 in a counter-clockwise direction.

Bearing blocks 130 (Fig. 2) are secured to the longitudinal angle members 101 and support a shaft 130' on which a sprocket 132 is eccentrically mounted. One end of a chain 133 is secured to the gear wheel 127 near the outer periphery thereof. The chain 133 passes over the sprocket 132 and extends downwardly and is mounted at its other end on a boss 134 on a collar 135 mounted on the tube 106.

It will thus be seen that as the gear wheel 127 rotates, the elevator 110 will be raised and lowered by means of the chain 133. The eccentric sprocket 132 is so set as to provide means to control the movement of the elevator so that the elevator starts to rise slowly, travels faster during the middle of its motion, and then goes slowly as it reaches the top of its stroke. The movement is similar as the elevator descends.

A shaft 140 (see Figs. 3 and 4) is pivotally mounted between the longitudinal angle members 101 and has an arm 141 secured thereto. The arm 141 extends downwardly and then inwardly and has a switch 142 mounted thereon. The switch 142 includes an operating arm 143. The operating arm 143 has a roller 145 rotatably mounted thereon which is adapted to engage a cam 146 on the rim of the gear wheel 127. The switch 142 controls the motor 123 and the construction is such that when the roller 145 engages the cam 146 the switch 142 shuts off the motor 123.

As shown the wheel engages the cam when the elevator is in lowered position. A tension spring 148 has one end thereof secured to the bearing bracket 129 and thus normally urges the support arm downwardly.

Also mounted on the shaft 140 I provide an upwardly extending trigger member 149 which is

adapted to be rocked by engagement with a box delivered upon the elevator platform, as will be later described. A stop member 150 is secured to the transverse angle member 100 and is positioned slightly behind the trigger member 149 and is adapted to be engaged by a box delivered to the elevator to thus limit the movement of the trigger member 149.

Attached to the frame member 103 and located below the supporting arm 141 I provide a rocking member 131' adapted to engage the lower side of the supporting arm 141 and thus prevent said supporting arm from dropping below the position necessary for its operation.

Angle members 151 which extend upwardly from the channel member 121 and the angle member 122 have inwardly extending legs adapted to be engaged by rollers 152 (see Fig. 5) on opposed ends of arms 153 which extend through the collar 135. Thus any tendency for the tube 106 to bind in the collar 105 as the elevator is raised is eliminated.

A stacking trough 165 is secured to the cross member 61 and by means of angle members 166 is secured to transverse members 62 and 62'. The lower end of the trough 165 is outwardly flared as at 167 to act as guides for a box being raised by the elevator. A rod 168 extends downwardly along one side of the trough 165 and at the top thereof extends inwardly over the trough.

A switch 169 is mounted on one of the angle members 166 and includes an operating arm 170 through which the rod 168 slidably extends. A collar 171 on the rod 168 engages the top of the operating arm 170 and a compression spring 172 engages the bottom of the operating arm 170 and is held in place by a collar 173 on the rod 168. The rod 168 extends downwardly and engages a tongue 174 secured to the cross channel 72. The switch 169 controls the motor 167.

A pair of frame members 180 are secured to the uprights 60a and 60b and extend therefrom at substantially right angles to the frame members 14. Mounted on each frame member 180 is a bearing bracket 181. The bearing brackets 181 support a shaft 182 on which are mounted a pair of sprockets 183 and one end of a pair of channel guides 184. The channel guides 184 extend between the uprights 60a and 60b and are positioned adjacent opposed sides of the elevator platform 110. Each channel guide 184 includes downwardly extending side portions 186 which pivotally support therebetween a sprocket 187.

The channel guides support the upper and lower reaches of continuous chains 188, the ends of which are supported by the sprockets 183 and 187 (see Fig. 5). The channel guides extend beyond the sprockets 187 and at the ends thereof are joined by a rod 189 (see Fig. 2). When in lowered position, the channel guides 184 are adapted to rest on blocks 185 mounted on one of the members 101 (see Figs. 2 and 5).

The rod 189 has a boss 190 thereon (Fig. 5) to which a piston rod 191 is mounted. The piston rod 191 moves in a cylinder 192 the lower end of which is pivoted at 193 to a boss 194 on the channel 121.

The cylinder 192 includes an air outlet (not shown) so that air may be allowed to enter the cylinder below the piston as the piston rises and to slowly escape therefrom as the piston descends.

A rod 200 extending between the uprights 60 and 60c is pivotally secured thereto. The rod 200 has two depending notched arms 201 thereon and a further depending actuating arm 202 to

the lower end of which one end of a tension spring 203 is secured. The other end of the spring is secured to a rod 204 extending between the channel members 102 and 104. The notched portions of the arms 201 are adapted to receive the ends of the rod 189 when the channel guides are in raised position.

Extending between the frame members 180 is an angle member 211 (Fig. 5) on which upwardly extending legs 212 are mounted, the legs 212 supporting a channel beam 213 upon the tops thereof. On the beam 213 rests one end of a pair of channel guides 214, the other ends of which are mounted on the shaft 182. The channel guides 214 each include downwardly extending side portions between which sprockets 215 are supported.

Mounted on the frame members 180 I provide bearing blocks 216 which support a shaft 217 upon which sprockets 218 are mounted. The sprockets 218 support one end of continuous chains 219 which may extend to any desired location and which may be driven by any suitable means.

Mounted on the shaft 182 I provide sprockets 222 which are located at the ends of the channel guides 214 previously mentioned. The sprockets 222 support one end of continuous chains 223 which are supported at the other end by the sprockets 215.

Outside of the sprockets 222 on the shaft 221 I arrange sprockets 183 which in turn support and drive the continuous chain 188 previously mentioned. The shaft 182 is extended at each end beyond the bearing brackets 181. At one side, nearest the feed conveyor, the shaft 182 supports a sprocket 226 which supports the upper end of a continuous chain 227 (Fig. 5). The lower end of the chain 227 is supported by a sprocket 228 (Fig. 2) which is driven by a motor 229 which operates continuously when the stacking apparatus is in operation.

At the other end the shaft 182 supports a sprocket 230 which supports one end of a continuous chain 231, the other end of the chain being supported by a sprocket 232.

A roller 233 (Fig. 11), rotatable on an adjustable supporting arm 234, mounted on one of the frame members 180 engages the chain 231 and serves to keep this chain tight at all times.

Pivottally mounted on a boss 236 on the angle member 211 I arrange a trip release member 237 (Fig. 5) having an upwardly extending portion 238 thereon which is adapted to be engaged by the lower box of a stack of boxes being discharged from the stacking mechanism. The trip release member extends downwardly and has one end of a rod 239 connected thereto. The rod 239 extends rearwardly and has a tube 240 at the rear end thereof into which a rod 241 extends. The rod 241 is connected to the arm 202. The rod 241 has a collar 242 thereon to limit the movement of the rod into the tube 240. One end of a tension spring 243 is secured to the downwardly extending part of the trip release 237, while the other end is secured to a depending arm 244 secured to a crosspiece 245 (see Fig. 1) between the channel guides 214.

Frame members 98 and 100 are extended beneath the discharge conveyor and at their outermost ends are supported by rods 100' (Fig. 5) whose uppermost ends are attached to the lower surface of the angle members 211 and have extending arms 246 attached thereto. The arms 246 at their outermost ends are connected to

arms 247 which latter have their upper ends connected to a cross angle member 248 (Fig. 1) extending intermediate the frame members 180. Rods 248' have one end pivotally attached to the ends of arms 246 and 247.

The other ends of the rods 248' threadedly engage turnbuckles 249. Other rods 250 threadedly engage the opposite side of the turnbuckles 249 and extend forwardly and pivotally engage the lower ends of downwardly extending levers 251. The levers 251, at their uppermost ends are pivotally attached to the channel guides 184 as at 252 and extend slightly above the channel guides 184 and have forwardly extending portions 253 which are adapted to engage the bottom of a box resting on the elevator platform 110 and raise it upwardly until the box is engaged by the discharge conveyor. The portions 253 which engage the lowermost box are pivotally supported at one end, as at 252, on the channel guides and also pivotally engage one end of the rods 250 (Fig. 5) immediately below the pivot 252. The channel guides are pivoted on the shaft 182 and the other ends of the rods 250 turn about pivots on the lower ends of the arms 247, the latter pivots being substantially below the shaft 182. The construction provides a parallel link motion for the portion 253 and as a result this portion 253 will keep its top surface always in a substantially horizontal position while being raised and lowered with the discharge conveyor.

A shaft 254 journaled in bearing blocks 255 arranged on the extension of the frame members 98 and 100 and adjacent the uprights 60a and 60b (see Fig. 1) supports cams 256 adapted to engage rollers 257 (see Fig. 5) supported by brackets 258 arranged on the lower face of the channel guides 184 to move the discharge conveyor to the raised position.

At the uppermost end of the stacking trough 165 (see Fig. 3) I provide a plate 259 mounted on a shaft 260. At one end thereof the shaft 260 has an arm 261 (see Fig. 12) which pivotally engages a rod 262, the lower end of which engages the approximate center of an arm 263 which is pivotally attached to the upper flange of the cross member 61 adjacent to the upright 60c. At its outer end the arm 263 is pivotally attached to a rod 264 (see Figs. 5, 11 and 12) extending downwardly and pivotally engaging a crank 265 (see Fig. 12) at the approximate center thereof. The crank 265 is attached to the shaft 140, the end of which is extended through the frame member 101.

A piston rod 266 is mounted on the outer end of the crank opposite the shaft 140 and moves in a cylinder 267, the lower end of which is attached to an arm 268 (see Fig. 12) which is attached to the upright 60c. A tension spring 269 (Fig. 11) having its upper end attached to the upper end of the piston rod 266 and its lower end attached to the arm 268 adjacent the connection of said arm to the upright 60c tends to urge the crank 265 downwardly.

Eccentrically mounted on the shaft 140 I provide an elongated member 270, being held in place by a set screw 270a (see Fig. 16). A sleeve 270b is arranged about this member 270 and supports (as by welding) on its upper side the switch arm 149. The switch lever 141 is similarly mounted on the lower side of the sleeve 270b. A second eccentrically mounted member 271 is also mounted on the shaft 140 and has a sleeve 271a mounted thereon, which is similar to sleeve 270b heretofore described. Sleeve 271a has mounted

on its upper side, by means of welding, a trigger arm 272 similar to the trigger arm 149.

The shaft 140 then extends through a raised portion 273 on the other member 101 and has another eccentrically mounted member 274 which is similar to the member 271.

A rod 275 has one end connected to the member 274 and the other end connected to the member 271 to form a rigid connection between the two.

Attached to the frame member 100 I also provide an upwardly extending stop member 276 upon which a stop arm 277 is mounted. The stop arm includes adjustable members 278 which are threaded and are adapted to engage the trigger arms 149 and 272 when either is moved backwardly.

Pivottally attached to the end of the frame member 101 I provide a lock release arm 279 which passes through a guide member 280 which is attached to the upright 66b. The lock release arm 279 has its end engaged with a catch member 281 pivotally supported by a pin 281' (see Fig. 13) in a cylindrical member 282 supported on the shaft by a key 254" and held in place by a collar 254' which threadedly engages a shaft 254. A compression spring 282' mounted in a hole 282" in the member 282 tends to urge the catch member 281 outwardly. An outwardly extending rod 283 is mounted on the member 274 and is disposed to engage the lower side of a stop rod 283' which projects from the upper face of the guide member 280 to limit its upward movement. The rod 283 when the trigger member 272 is depressed moves the arm 279 downwardly.

The arm 279 has a downwardly extending portion 284 which engages the upper end of a tension spring 285, the lower end of which is supported by the lower end of the guide 280. The spring 285 tends to urge the lock release arm 279 in an upwardly direction.

Disposed between the cylindrical member 282 and the sprocket 232 and rotatably mounted on the shaft 254 and attached to the sprocket 232 by means of a pin 232' I provide a larger cylindrical member 286 having in its face a series of inner slots 287 which are adapted to engage the catch 281.

In operation, a box being conveyed by the belt conveyor 23 is delivered thereby onto the chains 27, which carry it toward the elevator platform 110. Assuming that the elevator and discharge conveyor are both in lowered position, as shown in Fig. 2, box passes over the spring plate 45 without actuating the switch 40 (as previously described), passes over the stop member 46 and onto the cylinder 67. A guide member 310 is secured to each of the uprights 60 and 60a. The guide members serve to guide the box as it is delivered onto the cylinder 67. The cylinder 67 urges the box onto the elevator rollers 114 and against the trigger member 149. Any tendency of the box to bounce back from the trigger member is eliminated by the spring loaded plate or apron 116 on the elevator platform.

When the box engages the trigger member 149, the member 270b is rotated, thus raising the arm 141 and thereby raising the switch roller 145 from engagement with the cam 146. This actuates the switch 142 and turns on the motor 123. The motor 123 drives the gear 126 which rotates the gear wheel 127, which by means of a chain 133 raises the elevator with the box thereon. As the box is raised from engagement with the trigger member 149, the switch 142 is lowered by

means of the spring 148. At this time the cam 146 has rotated away from the switch roller 145 and the motor 123 continues to drive the gear wheel 127 until the cam again engages the switch roller 145.

As the box is raised by the elevator, the box engages the cross channels 72 and forces the arms 71 outwardly. The elevator raises the box slightly above the cross channel 72 at which time the arms 71 resume their original position (see Fig. 3) and support the box thereon. If the box should be too long, or should extend too far under the cross channel 72 adjacent the feed conveyor, the box would raise the extensible arms and tongue 174 would actuate the switch 169 and thus shut off the motor 123.

When the elevator rises, the lever 37 is rocked and thus lowers the chains 27. A further box being conveyed by the chains 27 will press the spring plate 45 and actuate the switch 40, as previously described, and will be urged against the stop member 46. When the elevator descends, the chains 27 are raised and the switch 40 is released and a further box is delivered to the elevator.

When the next to the last box is raised by the elevator it will cause the top box of the stack to strike the plate 259 and by means of the rods 262 and 264 and the eccentrics 270 and 271 move the trigger member back of the stop member 276 (see Figs. 14 and 15) so that it cannot be actuated by the next box conveyed upon the elevator platform. This box also will move the trigger member 272 forward of the stop member 276 and into position to be actuated by the next incoming box.

When the last box strikes the trigger member 272, it, by means of the rod 275, moves the member 274 to move the rod 283 in a downward direction, thereby moving the arm 279 in the same direction and allowing the lock 281 to be extended and engaged in the next slot 287 that comes into position on the constantly rotating member 286. The chains 231 then rotate the shaft 254 and the cam 256 engage the rollers 257 and lift the forward end of the discharge conveyor also lifting the last or lower box of the stack from the elevator. This lower box is then raised to engage the next to the bottom box of the stack to thus complete the stack.

The stack is then conveyed away from the elevator. The stack being thus discharged engages and rocks the trip release member 238 which moves the rods 239 and 241 and thus rocks the arm 292 and releases the rod 189 from the notched arms 201 and allows the channel guides to resume their lowered position. Also at the time the boxes are discharged the contact is removed from the plate 259 which allows the switch arms 149 and 272 to resume their original position, and lock release arm 279 is again raised to engage the lock 281 and depress said lock from engagement with the slots 287 in the member 286.

If the boxes within the trough should be raised too high, the uppermost box would engage and raise the rod 168 and actuate the switch 169 and thus shut off the motor 123.

The chain 133 is sufficiently long so that a slack portion 133a is provided. When the motor is started this slack must first be taken up and as a result a better lifting and lowering operation of the elevator is secured.

Having thus described my invention and the present preferred embodiments thereof I desire to emphasize the fact that many modifications may be resorted to in a manner limited only by a just interpretation of the following claims.

Having thus described my invention, I claim:

1. In a box handling apparatus, an elevator, means to operate said elevator, a stacking trough positioned in the path of movement of a box on said elevator, means to deliver boxes to said elevator, means to support boxes raised in said trough to form a stack, a discharge conveyor operable to discharge a stack of boxes from said trough, said discharge conveyor including a pivoted frame having endless conveyor chains mounted to move thereon, said discharge conveyor having an end portion disposed in the path of movement of boxes in the stacking trough, said discharge conveyor frame being mounted to move from a lower position below the position occupied by the elevator when in its lowermost position to an upper position above the position occupied by the elevator when in its lowermost position and to raise a box on the elevator as it moves upwardly, cam means engaging said frame to lift the frame, means to operate said cam means to raise said discharge conveyor above the elevator so that the discharge conveyor engages and lifts a box on the elevator permitting the lifted box to engage the next higher box in the stack, means to operate the discharge conveyor chains to move the stack from the stacking trough.
2. In a box handling apparatus, an elevator, means to operate said elevator, a stacking trough positioned in the path of movement of a box on said elevator, means to deliver boxes to said elevator, means to support boxes raised in said trough to form a stack, a discharge conveyor operable to discharge a stack of boxes from said trough, said discharge conveyor including a pivoted frame having endless conveyor chains mounted to move thereon, said discharge conveyor having an end portion disposed in the path of movement of boxes in the stacking trough, said discharge conveyor frame being mounted to move from a lower position below the position occupied by the elevator when in its lowermost position to an upper position above the position occupied by the elevator when in its lowermost position and to raise a box on the elevator as it moves upwardly, cam means engaging said frame to lift the frame, means to operate said cam means to raise said discharge conveyor above the elevator so that the discharge conveyor engages and lifts a box on the elevator permitting the lifted box to engage the next higher box in the stack, means to hold said discharge conveyor in raised position and means to release the discharge conveyor to move the stack from the stacking trough and means to permit the discharge conveyor to move to its lower position below the position occupied by the elevator when the latter is lowered.
3. In a box handling apparatus, an elevator, means to operate said elevator, a stacking trough positioned in the path of movement of a box on said elevator, means to deliver boxes to said elevator, means to support boxes raised in said trough to form a stack, a discharge conveyor operable to discharge a stack of boxes from said trough, said discharge conveyor including a pivoted frame having endless conveyor chains mounted to move thereon, said discharge conveyor having an end portion disposed in the path of movement of boxes in the stacking trough, said discharge conveyor frame being mounted to move from a lower position below the position occupied by the elevator when in its lowermost position to an upper position above the position occupied by the elevator when in its lowermost position and to raise a box on the elevator as it moves upwardly, cam means engaging said frame to lift the frame, means to operate said cam means to raise said discharge conveyor above the elevator so that the discharge conveyor engages and lifts a box on the elevator permitting the lifted box to engage the next higher box in the stack, means to hold said discharge conveyor in raised position and means to release the discharge conveyor to move the stack from the stacking trough and means to permit the discharge conveyor to move to its lower position below the position occupied by the elevator when the latter is lowered.
4. In a box handling apparatus, an elevator, means to operate said elevator, a stacking trough positioned in the path of movement of a box on said elevator, means to deliver boxes to said elevator, means to support boxes raised in said trough to form a stack, a discharge conveyor operable to discharge a stack of boxes from said trough, said discharge conveyor including a frame, means intermediate the length of the frame to pivotally support the frame, said discharge conveyor having an end portion disposed in the path of movement of boxes in the stacking trough, said discharge conveyor frame being mounted to move from a lower position below the position occupied by the elevator when in its lowermost position to an upper position above the position occupied by the elevator when in its lowermost position and to raise a box on the elevator as it moves upwardly, means to lift said end portion of the discharge conveyor so that the discharge conveyor engages and lifts a box on the elevator, permitting the lifted box to engage the next higher box in the stack, means to hold said discharge conveyor in raised position and means to operate the discharge conveyor to move the stack from the stacking trough.
5. In a box handling apparatus, an elevator, means to operate said elevator, a stacking trough positioned in the path of movement of a box on said elevator, means to deliver boxes to said elevator, means to support boxes raised in said trough to form a stack, a discharge conveyor operable to discharge a stack of boxes from said trough, said discharge conveyor having an end portion disposed in the path of movement of boxes in the stacking trough, means to mount said discharge conveyor for bodily upward movement from a lower position below the position occupied by the elevator when in its lowermost position to an upper position above the position occupied by the elevator when in its lowermost position and to raise a box on the elevator as it moves upwardly, means to lift the discharge conveyor so that the discharge conveyor engages and lifts a box on the elevator, permitting the lifted box to engage the next higher box in the stack, means to hold said discharge conveyor in raised position, means to operate the discharge conveyor to move the stack from the stacking trough, and means to release the discharge conveyor holding means to permit the discharge conveyor to move to its lower position below the position occupied by the elevator when the latter is lowered.
6. In a box handling apparatus, an elevator, means to operate said elevator, a stacking trough positioned in the path of movement of a box on said elevator, means to deliver boxes to said ele-

vator, means to support boxes raised in said trough to form a stack, a discharge conveyor operable to discharge a stack of boxes from said trough, said discharge conveyor including a frame, means to pivotally support the frame, said discharge conveyor having an end portion disposed in the path of movement of boxes in the stacking trough, said discharge conveyor frame being mounted to move from a lower position below the position occupied by the elevator when in its lowermost position to an upper position above the position occupied by the elevator when in its lowermost position and to raise a box on the elevator as it moves upwardly, means to lift the frame so that the discharge conveyor engages and lifts a box on the elevator to engage the next higher box in the stack, means to hold said discharge conveyor in raised position, means to operate the discharge conveyor to move the stack from the stacking trough and means to release the discharge conveyor holding means to permit the discharge conveyor to move to its lower position below the position occupied by the elevator when the latter is lowered.

7. In a box handling apparatus, an elevator, means to operate said elevator, a stacking trough positioned in the path of movement of a box on said elevator, a feed conveyor adapted to deliver boxes to said elevator, means to support boxes

raised in said trough to form a stack, a discharge conveyor operable to discharge a stack of boxes from said trough, said discharge conveyor comprising a pivoted support frame having conveying means thereon, said discharge conveyor including an end portion disposed below and in the path of movement of boxes in the stacking trough, said discharge conveyor frame being mounted to move from a lower inoperative position below the position occupied by the elevator when in its lowermost position to an upper operative position above the position and to raise a box on the elevator in moving to upper operative position, means actuated by the delivery of each box except the last box of a stack onto said elevator to actuate said elevator means and to thereby raise and lower said elevator, means to prevent further operation of said elevator operating means after the elevator descends after raising the next to last box of a stack, means to move said discharge conveyor from its lower inoperative position to its raised operative position when the last box of a stack is placed on the elevator whereby the last box is moved upwardly by the discharge conveyor to engage the next higher box in the stack, and means to thereafter operate the discharge conveyor chains to move the stack from the stacking trough.

AMBROSE NEJA.
